CLAIM

The ornamental design for a display screen with graphical user interface, as shown and described.

DESCRIPTION

The sole FIGURE is a front view of a display screen with graphical user interface according to the design.

The broken lines illustrate portions of the display screen with graphical user interface that form no part of the claimed design. The broken line showing of the display monitor is provided for the purpose of illustrating environmental structure and forms no part of the claimed design. All other broken lines showing text of the graphical user interface form no part of the claimed design.

1 Claim, 1 Drawing Sheet
